UNITED STATES PATENT OFFICE.

JOSEPH W. BRONNER, OF BALTIMORE, MARYLAND.

CAN ATTACHMENT.

1,221,666.

Specification of Letters Patent.

Patented Apr. 3, 1917.

Application filed January 21, 1916. Serial No. 73,392.

To all whom it may concern:

Be it known that I, JOSEPH W. BRONNER, a citizen of the United States, residing at Baltimore, in the State of Maryland, have 5 invented new and useful Improvements in Can Attachments, of which the following is a specification.

This invention relates to a can attachment and more particularly to an attachment 10 whereby the lid may be held against displacement and the can properly carried.

The primary object of the invention is to provide an attachment of the character specified of simple construction which can 15 be readily attached to and detached from a can so that upon defect in the can the attachment can be used for another can, thus preventing the expense of constructing a handle and fastener for each can.

20 An object of the invention is to provide an attachment for cans that can be readily removed thus allowing the attachment to be used over and over again and not to be discarded when the can is rendered useless.

25 A further object of the invention is to provide an attachment of simple construction capable of frictionally engaging the bead of a can for positively preventing the displacement of the cover, the attachment 30 at the same time acting in the capacity of a handle.

With these and other objects in view the invention consists in the construction, combination and arrangement of parts as will 35 be hereinafter more fully described, illustrated in the accompanying drawing and pointed out in the claim hereunto appended.

In the drawings:—

Figure 1 is a top plan view of a can showing 40 my attachment applied thereto.

Fig. 2 is a similar view showing the can and the attachment in side elevation.

Fig. 3 is a detailed vertical sectional view.

Fig. 4 is a detailed vertical sectional view 45 of a modification.

Fig. 5 is a detailed sectional view of a further modification.

Fig. 6 is a view illustrating the manner in 50 which the handle and the cross bar may be separated.

Referring to the drawing the numeral 1 designates the body of the can having its upper edge portion formed with an annular member defining a bead 2 and including a 55 U-shaped flanged member 3 extending inwardly from the edge of the can. Fric-

tionally engaging the flange 3 is a cover 4 depressed as indicated at 5 so as to provide an upwardly extending flange 6, the latter being the portion that engages the flange 3. 60

My attachment comprises a cross rod 7 made of heavy grade of wire or any suitable material and as shown has its extremities formed into hooks 8 engaging under the bead 2. At this point attention is called 65 to the fact that when arranging the rod 7 in position the same is moved across the can until the hook shaped extremities frictionally engage the bead of the can and this friction is increased until a degree of pressure is reached which will prevent the rod from accidentally moving from the bead. When the rod is in this position its intermediate portions thereof engage the edge portion of the flange 6 with the result that the 70 cover 4 is prevented from moving in a direction to leave the can and to also hold the flange 6 in its proper tight engagement with the flange 3. The member 8' that forms the handle of my attachment is given an ar- 75 cuate shape and the extremities thereof are formed into eyes 9 so as to encircle an intermediate portion of the rod 7, to allow the handle to have a swinging movement so as to either lie in the depression 5 when in an inoperative position or to extend at right angles to the plane of the top when in an operative position. The handle located as 80 shown is obviously held against sliding movement on the bar to an extent which 85 would cause the handle to engage the side walls of the can and the end portions of the bar when the can is tilted by grasping the handle. Engagement of this character frequently takes place when the usual handle 90 or bail is connected with the usual ears on the sides of a bucket, and when the trans- 95 verse bar is employed the same result should follow except for the provision of confining the handle by means of the flanges spaced 100 from the outer wall of the can.

The construction of the device illustrated in Fig. 4 of the drawing is identical with that illustrated in Figs. 1 to 3 inclusive with the exception that the cross rod 10 is depressed at the point 11 so as to accommodate the different construction of can in which the upper most edge 12 of the cover 13 is disposed slightly below the upper edge 14 of the body of the can. 105

In Fig. 5 of the drawing I have so shaped the cross rod 15 as to accommodate a can 110

the cover of which has a diameter equal to the diameter of the body of the can. In this particular instance each end portion of the cross rod 15 is initially bent at right angles 5 as shown at 16 and then subsequently at an angle to engage under the bead 17 of the can body.

At this point I wish to call attention to the fact that although I have only illustrated 10 three different constructions of cans I wish it to be understood that in slightly changing the configuration of the cross rod I am able to accommodate many other constructions of cans.

15 The extremities of the rod and the eyes of the handles of my attachment bear the relation as clearly illustrated in Fig. 6 of the drawings wherein it will be seen that the proportion of the extremities of the cross 20 rod and the eyes of the handle is such that the former can readily pass through the latter so that a cross rod may be used independent of a handle or vice versa.

From the foregoing description taken in 25 connection with the accompanying drawing it should be apparent that I provide a device which is admirably adapted for the purpose for which it is intended, that the device is simple, durable, and efficient of con-

struction and that the device may be manufactured and sold at a comparatively low cost.

The change in the form, proportion and minor details of construction may be made within the scope of the claim without departing from the spirit or sacrificing any of the advantages of the invention.

What I claim is:—

The combination with a can formed with an annular member defining a bead at the outer edge of the can and including a U-shaped flanged member extending inwardly from the edge, of a cover having a depressed top and a flange passing over the top of the flange first mentioned, a bar passing across the top of the can and across the flange of the cover and having turned-over end portions engaging the bead, and a handle pivotally connected with the bar and having its ends positioned within the flange of the 45 cover, said flange preventing the displacement of the handle on the bar.

In testimony whereof I affix my signature in presence of two witnesses.

JOSEPH W. BRONNER.
